CLAIM

The ornamental design for an adherent pad, as shown and described.

DESCRIPTION

FIG. 1 is a front perspective view of an adherent pad in accordance with my design, showing an environment of a human torso;

FIG. 2 is a front perspective view thereof;

FIG. 3 is a rear perspective view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a right side elevation view thereof; and,

FIG. 9 is a left side elevation view thereof.

The broken lines illustrate portions of the environment and adherent pad which form no part of the claimed design.
